UNITED STATES PATENT OFFICE.

JOHN JAMES HANNA, OF QUANAH, TEXAS.

STOVE.

1,164,510.

Specification of Letters Patent. Patented Dec. 14, 1915.

Application filed May 20, 1915. Serial No. 29,361.

To all whom it may concern:

Be it known that I, JOHN J. HANNA, a citizen of the United States, residing at Quanah, in the county of Hardeman and 5 State of Texas, have invented certain new and useful Improvements in Stoves; and I do declare the following to be a full, clear, and exact description of the invention, such as will enable others skilled in the art to 10 which it appertains to make and use the same.

My invention relates broadly to improvements in heating apparatus and more particularly to stoves designed primarily for 15 the burning of coal and the like.

The object of the invention is to improve upon stoves of this class to such an extent as to provide a heater which, although being of very simple and inexpensive construction, will be highly efficient in operation and 20 will possess a number of advantageous features.

With this general object in view, the invention resides in certain novel features of 25 construction and the unique combination of parts hereinafter fully described and claimed.

In describing the invention, I shall refer 30 to the accompanying drawings wherein like reference characters designate corresponding parts throughout the several views and wherein;

Figure 1 is a vertical section of a stove 35 constructed in accordance with my invention; Fig. 2 is a similar view as seen along the plane indicated by the line 2—2 of Fig. 1; Figs. 3, 4 and 5 are horizontal sectional views taken respectively on the lines 3—3, 4—4 and 5—5 of Fig. 2.

40 In these drawings which constitute a part of the application, the numeral 1 indicates an upright cylindrical shell which may be formed of sheet metal or in some cases may be cast. Sheet metal, however, is preferable in view of the fact that its use is much 45 more inexpensive. The upper end of the shell 1 is closed by a top 2 preferably in the form of an ornamental metal casting having a depending flange 3 which fits snugly 50 within the shell 1 and is secured thereto by stove bolts or the like 4, one edge portion of the top 2 being provided with a fuel door 5, while the diametrically opposite edge portion thereof is equipped with the usual 55 standing flange 6 for the attachment of the ordinary stove pipe.

The lower end of the cylindrical drum 1 is closed by a solid bottom 7 preferably having an upstanding flange 8 projecting into and bolted to the shell, and a depending annular flange 9 serving as a base to rest upon the floor. Needless to say, the use of the flange 9 is not absolutely essential, since ornamental legs could well be provided in place thereof. 60

Spaced a suitable distance above the bottom 7, is a horizontally disposed partition 10 shown in the present application as provided with a depending flange secured by stove bolts to the shell 1. The center of the 70 partition 10 is provided with a circular opening 11 beneath which an oscillatory grate 12 is disposed, this grate being preferably, though not necessarily, supported by the brackets 13. Needless to say, the space 75 between the grate 12 and the bottom 7 constitutes an ash pit into which any preferred type of door 14 leads, such door preferably having a damper as is common with devices of this class. 80

Projecting into the central opening 11 in the partition 10 is the lower contracted end of the inverted cone-shaped fire-pot 15, said end being shown in the present embodiment of the invention as provided with an outstanding annular flange 16 overlying the partition 10 and limiting the insertion of said end into the opening 11. It will be observed by reference to the drawings that although the lower end of the fire-pot 15 is 90 spaced a considerable distance from the shell 1, the upper end of said pot is disposed in contact with and secured to the intermediate portion of said shell by stove bolts or the like 17, the space between the pot 15 and 95 the shell 1 constituting an air heating jacket.

The upper end of the fire-pot 15 is provided with one or more openings 18 from which hot air outlet channels 19 rise to openings 20 formed in the upper end of the 100 shell 1, while discharging into the lower end of the air heating jacket, is a fresh air inlet 21. Thus it will be seen that when fuel is burning within the pot 15 and cool air is allowed to enter the air heating jacket 105 through the inlet 21, the temperature of this air will be raised considerably, such air being then discharged through the openings 20 into the room and thus affording sources of heat which, when coating with the heat 110 radiating from the shell, cause the stove to be a highly efficient heater.

The fresh air inlet 21 is shown in the present embodiment of the invention as depending from an opening in the partition 10 through the bottom 7 and through the floor upon which the stove rests, this inlet being in the form of a pipe open at its lower end and having in one side a supplemental air inlet opening 22, the side of which may be varied by an appropriate damper 23, while the amount of fresh air entering the open lower end of the pipe may be controlled by an additional damper 24. In some cases, it may be undesirable to have the inlet 21 depend from the stove, on account of the fact that this construction necessitates the forming of an opening through the floor through which said inlet may pass, but this objection may be readily overcome by leading the inlet through one side of the shell 1 into the air heating space, as will be readily understood by those skilled in the art to which the invention relates.

Although the use of the same is not absolutely essential to the correct working of the stove, I preferably provide an oscillatory horizontal agitating bar 25 disposed in contact with and shiftable laterally over the upper side of the grate 12, whereby clinkers and the like may be dislodged from said grate, the bar in question being adapted to be actuated by any one of the numerous types of shaker bars now on the market or by any preferred design of such bar. The designs of the free end of the bar 25, however, and that of the projection 26 on the grate 12, are preferably the same, whereby the same shaker bar may be applied to use for actuating both members.

From the foregoing description taken in connection with the accompanying drawings, it will be evident that although comparatively simple construction has been provided for carrying out the object of the invention, the stove will be very efficient in operation and will possess a number of advantageous features. Particular emphasis is laid upon the fact that the fire-pot 15 gradually extends toward the shell 1 from its lower to its upper end, since by this construction, a thick sheet of air surrounds the lower end of the pot and is warmed thereby, whereas when this heated volume of air rises to the upper end of the pot, the sheet of air presented thereto is comparatively thin, thus allowing the temperature of such sheet to be again raised before the air is expelled through the hot air outlets. The fact that these outlets lead through the fire-

pot is also considered a unique feature of the invention, since super-heating of the air is thus accomplished.

In the drawings, certain specific details of construction have been shown for accomplishing probably the best results and for allowing the entire stove to be disassembled at will, and in the preceding description, such details have been described, but it will be evident that I need not be limited to such details or to character of materials and proportion of parts, otherwise than to the extent to which the appended claim restricts me.

I claim:—

A stove comprising an upright cylindrical shell closed at its upper and lower ends and having at opposite points near the upper end of its curved wall a pair of air outlet openings, a horizontal partition near the lower end of said shell formed with a central circular opening, a fire bowl having its lower end inserted snugly into the opening in said partition, said bowl being gradually increased in diameter from its lower to its upper end and having the latter disposed in contact with the inner side of the aforesaid wall in a horizontal plane immediately below the air outlet openings, said fire bowl having near its upper end a pair of air outlet openings disposed immediately beneath the aforesaid openings in the wall, fasteners passing through the contacting parts of the wall and bowl, a pair of upright plates secured at their lower ends to the bowl directly below the air outlet openings therein, said plates having their upper ends bent laterally into contact with the aforesaid wall immediately above the air outlet openings in said wall, the upright side edges of said plates being bent laterally into contact with the wall and bowl on opposite sides of the openings therein and being here again bent laterally to form attaching flanges contacting with said wall and bowl, fasteners passing through said flanges and through the wall and bowl, and an upright air supply pipe rising through the closed lower end of the shell and opening through the partition into the space surrounding the bowl.

In testimony whereof I have hereunto set my hand in presence of two subscribing witnesses.

JOHN JAMES HANNA.
